Geo. E. Thackray
ATTORNEY

UNITED STATES PATENT OFFICE.

FRANK I. WHITE, OF JOHNSTOWN, PENNSYLVANIA.

ROLLING-MILL GUIDE.

1,325,343.

Specification of Letters Patent. Patented Dec. 16, 1919.

Application filed February 18, 1918. Serial No. 217,741.

To all whom it may concern:

Be it known that I, FRANK I. WHITE, a citizen of the United States, and a resident of the city of Johnstown, county of Cambria, and State of Pennsylvania, (whose post-office address is No. 218 Fairfield avenue, Johnstown, Pennsylvania,) have invented certain new and useful Improvements in Rolling-Mill Guides; and I do hereby declare the following to be a full, clear, and exact description of the invention, such as will enable others skilled in the art to which it appertains to make and use the same.

15 My invention relates to rolling mill guides with special reference to a construction that allows the adjustment of same around their longitudinal axes to provide for slight irregularities due to misplacement, malformation, wear or other causes. Although my invention is applicable to various forms of guides, such as straight guides which do not produce a twist in a rolled bar, it is particularly adapted to what is known as twist 20 guides and is so illustrated herein.

25 One of the features of my invention consists generally in mounting the guide in a holder, which is adapted to be rocked or rotated approximately around its axis on its curved or semi-circular base and held 30 in position by screws, wedges or other means, thus obviating the necessity of rotating the guide by itself, and also allowing the working portions of the guide to be made much 35 smaller and consequently cheaper and easier of replacement.

Having thus given a general description 40 of my invention, I will now, in order to make the matter more clear, refer to the annexed sheet of drawings, which forms part of this specification, and in which like characters refer to like parts.

Figure 1 is a vertical sectional elevation at right angles to the axes of the rolls, showing two sets of rolls of a continuous mill, illustrating the application of my invention.

Fig. 2 is a rear end elevation of the guide mechanism drawn on a larger scale.

50 Fig. 3 is a front end elevation of the guide mechanism.

Fig. 4 is a side elevation.

Fig. 5 is a top plan view of the guide mechanism embodying my invention.

Referring now to the characters of reference on the drawings:—1 is the housing of the receiving pair of rolls, 2 are the rolls thereof provided with a pass or groove 3. 5 is the twist guide, the tapered end of which is 4, adapted to fit in the curved space between the two rolls. This guide is preferably made in pairs or two portions which can be separated to allow a "cobble" to be easily removed, and their interior surfaces are formed with a twist or spiral, adapted 60 to receive what is known as an oval or bar of oval cross-section, the major axis of which issues substantially horizontally from pass 3 of the rolls, and the guide twists it until its major axis is substantially vertical 70 and adapted to enter the pass of the next set of rolls, which may be either round, square or approximately round or square. For this purpose it is necessary that the guide should lead and hold the bar with 75 the longer axis of its section upright immediately next to the pass in order that the reducing action of the rolls shall be accomplished in the direction of the major axis of the cross-section of the bar. Secured to 80 the roll housings is the guide rest bar 6, and on this is mounted the casing 7, provided with a projecting portion 8, adapted to fit in a corresponding groove in the rest bar and secured thereto through the hole 9 by 85 means of the bolt 10, the bolt head resting in the recess 11 in the casing. 12 are upwardly extending ears or lugs of the casing. 13 are holes in the ears 12, whereby the casing may be lifted from position, or a 90 bar may be introduced through the holes to wedge out the cross bar 15. 14 are grooves or recesses in the inner faces of the ears 12. 15 is a cross bar, the ends of which are adapted to be seated within the grooves 14. 95 16 are wedges adapted to be inserted between the cross bar 15 and the upper surfaces of the guide holder 17. The guide holder 17 fits loosely in the casing 7 and is provided with a curved lower portion 18, 100 which is slightly smaller than and adapted to loosely fit within the curved recess 19 in the casing 7. The guide holder is further provided with projecting flanges 20 adapted to contact with the ears of the casing and 105 prevent displacement of the guide holder, and has a groove or recess 21 adapted to receive the guides 5. Vertical grooves 22 are

also provided in the insides of the guide holder 17 adapted to receive the projections 23 formed on the guides 5 to assist in holding them longitudinally in position. 24 are 5 inclined grooves formed on the inside of the guide holder 7 adapted to receive the ends of a retaining bar 25, and 26 is a wedge adapted to be driven between the guides 5 and the retaining bar 25 to secure 10 the guides firmly in position within the guide holder. As shown at the left-hand of Fig. 1, 27 is a receiving guide adapted to receive the bar as it issues from the adjustable twist guide 5 and pass it into the 15 rolls on the left-hand side, the bar being indicated by the broken line and the direction of its movement by the arrows thereon.

My rolling mill guide may be axially adjusted in position by loosening the two 20 wedges 16 by driving them backward and then rotating the guide holder 17 either by hand or by light taps of a hammer or preferably by setting one of the wedges in position desired and then driving the other 25 wedge inwardly until both wedges become tight and the guide holder is in the required position, this action causing the guide holder to rotate substantially around the guide axis by reason of its curved lower surface 18, 30 which is substantially a semi-circle with its center as the guide axis, this convex surface 18 being adapted to fit and be supported within the curved recess 19 in the casing 7. Slight and accurate adjustments may be 35 made in this way and when the wedges are both driven tight, the guide and guide holder are firmly secured in position.

Although I have described and illustrated 40 my invention in considerable detail, I do not wish to be limited to the exact and specific details thereof as shown and described, but may use such modifications in, substitutions for, or equivalents thereof, as are embraced within the scope of my invention, as 45 pointed out in the claims.

Having thus described my invention, what

I claim and desire to secure by Letters Patent is:—

1. A rolling mill guide provided with a guide holder and means for securing said guide therein, said guide holder being mounted in a fixed casing and provided with means for rotatively adjusting said guide holder and contained guide in said casing.

2. A rolling mill guide comprising a pair 55 of grooved guides provided with a guide holder and means for securing same therein, said holder having a convex curved lower surface, a casing provided with a similar concave curved surface on which said guide 60 holder is mounted and adapted to be slightly rotated, and means for adjusting and securing said guide holder and contained guide within said casing.

3. A rolling mill guide provided with a 65 casing secured on a rest bar adjacent the rolls, said casing having side portions and a concave curved bearing surface near its lower portion, a guide holder fitted loosely within said casing and having a convex 70 curved lower surface adapted to be seated upon the concave curved surface of the casing, a cross bar removably mounted in said casing, and wedges inserted between said cross bar and said guide holder, whereby 75 said guide holder may be axially adjusted within said casing.

4. A rolling mill guide provided with a casing having an opening with a concave curved bottom, a guide holder mounted in 80 said opening and having a convex curved bottom loosely fitting within the opening of the casing, a removable cross bar mounted near the upper portion of said casing, wedges inserted between said guide holder and said cross bar, and means for securing the guide within said guide holder, whereby 85 said guide may be axially adjusted.

In witness whereof I hereunto affix my signature.

FRANK I. WHITE.
